UNITED STATES PATENT OFFICE.

ALVIDORE SHERMAN TRUSCOTT, OF BOZEMAN, MONTANA.

ALARM MECHANISM.

SPECIFICATION forming part of Letters Patent No. 623,747, dated April 25, 1899.

Application filed November 19, 1898. Serial No. 696,935. (No model.)

To all whom it may concern:

Be it known that I, ALVIDORE SHERMAN TRUSCOTT, residing at Bozeman, in the county of Gallatin and State of Montana, have invented a new and useful Alarm Mechanism, of which the following is a specification.

My invention relates to alarm mechanisms, and has for its object to furnish the several doors and windows with means for sounding an alarm when they are opened or raised.

A further object of my invention is to furnish any number of calling-stations, either in a single building or in separate buildings, with means for sounding an alarm at a convenient station or location.

A further object of my invention is to furnish an improved central alarm mechanism whereby the operation of any of the calls or the opening of a door or the raising of a window will sound an alarm-bell common to all of them and display on an indicating mechanism the number of the station operating the alarm.

With these objects in view my invention consists in the improved construction, arrangement, and combination of parts herein-after fully described and afterward specifically pointed out in the appended claims.

In order to enable others skilled in the art to which my invention most nearly appertains to make and use the same, I will now proceed to describe its construction and operation, reference being had to the accompanying drawings, in which—

Figure 1 is a view in front elevation of the box containing my central alarm mechanism, showing the indicators on the front and the alarm-bell on the top thereof, the indicators being in position to show that calls have been made at stations 1, 3, and 6. Fig. 2 is a view, on a larger scale, of the box with the front removed, showing the interior mechanism in elevation in normal condition ready to be operated from any station. Fig. 3 is a similar

view, on the same scale as Fig. 2, of the same parts, the upper portion being broken away and the mechanism in position showing that an alarm has been sounded from station 4. Fig. 4 is a vertical sectional view taken on the plane indicated by the broken line 44 of Fig.

2. Fig. 5 is a vertical sectional view taken on the plane indicated by the broken line 55

of Fig. 2. Fig. 6 is a vertical sectional view taken on the plane indicated by the broken line 66 of Fig. 3.

55

Like letters of reference mark the same parts wherever they occur in the various figures of the drawings.

Referring to the drawings by letters, A is a box having a front A', a back A², and sides A³ and A⁴. The front A' is hinged at its lower edge, as at A⁵ A⁶, and provided with a suitable lock and key. The front A' and back A² are provided with a series of oppositely-located parallel vertical equidistant grooves, as at 60 B, in which are located vertical tongues C of a series of weights C, and to each of these weights is attached a cord D, leading to a door, window shutter or sash, or a bell-pull or button at any station at which an alarm is 65 to be sounded. These cords all pass through a slot in a horizontal bar E, which is held normally down upon the weights by means of a cord F, secured at one end thereof, passing downward around a pulley F', upward and 70 over a second pulley F'', horizontally to and once or more around a pulley G, and thence downward, a weight H being attached to its end. 75

The horizontal bar E has at its opposite 80 end a vertical arm E', having side trunnions E², which engage in grooves H' in the inner faces of the two uprights H², located in the front and rear of the box.

To the arm E' of the bar E are pivotally 85 connected two parallel arms I I', the outer ends of which are pivotally connected between and to the outer ends of two pairs of parallel levers J J', whose inner ends are pivoted to the standards or uprights H, the 90 outer ends of the lever I and pair of levers J being pivotally connected to the outer ends of the lever I' and the pair of levers J' being pivotally connected to the ends of an upright link or bar K.

The pulley G has a series of tappet-pins G' projecting from the front thereof, which during the rotation of the pulley strike against and oscillate two levers L, which operate two strikers M and cause them to sound an alarm 100 on a gong N, mounted on top of the box.

Pivoted at their lower ends on brackets O', projecting from the front of the box, is a series of strips or covers O, which when up con-

ceal a series of numbers corresponding to the weights, there being a weight to each station. These strips O have each an arm O² at right angles to the strip, which when the strip is 5 up projects through a slot or hole O³ in the front A' into one of the grooves B and in the path of the corresponding weight C.

The operation of my invention may be described as follows: A door or window being 10 opened or disturbed or a call being made at a station, the cord D, leading to that door, window, or station, is pulled. This causes the weight C, attached to that cord, to be raised, carrying up the bar E with it, thus pulling 15 on the cord F, causing it to rotate the pulley G and sound the alarm. The weight H is also raised, and when the cord at the station is released the weight C, attached to it, will drop to its normal position and weight 20 H will return bar E to its normal position, turning pulley G in the opposite direction and continuing the alarm. In its upward movement the weight C will strike against arm O² of the cover O corresponding with the 25 weight, which will cause the strip or cover to rotate on its pivot and drop, uncovering and exposing the number indicating the door, window, or station at which the alarm has been sounded. Any lowered covers may be 30 raised by pulling the cord P. The arrangement of the levers I and J, in connection with the connecting-link K and arm E' of bar E, will cause the bar to always move in a horizontal line no matter by which weight it is 35 raised.

The advantages attending the use of my invention are numerous and will be obvious from the foregoing description, and while I have illustrated and described what I believe 40 to be the best means for carrying out my invention I do not wish to be understood as limiting myself to the exact construction and arrangement herein shown, but hold that such changes and variations as might suggest 45 themselves to the ordinary mechanic would properly fall within the limit and scope of my invention.

Having thus fully described my invention, what I claim as new, and desire to secure by 50 Letters Patent, is—

1. In an alarm mechanism, the combination of a series of weights, cords leading from said weights to the various alarm-stations, a lever resting on said weights, an alarm-bell and 55 means connected with the lever whereby movement thereof will sound the alarm, substantially as described.

2. In an alarm mechanism, the combination of a series of weights, cords leading from said weights to the various alarm-stations, a lever 60 resting on said weights, an alarm-bell, a cord leading from said lever, an alarm-pulley around which said cord passes, and a weight attached to said cord, substantially as described. 65

3. In an alarm mechanism, the combination of a series of weights, cords leading from said weights to the various alarm-stations, a lever resting on said weights, an alarm-bell, a cord leading downward from said lever, pulleys 70 around which said cord passes upward and horizontally, an alarm-pulley around which said cord passes, and a weight attached to the cord, substantially as described. 75

4. In an alarm mechanism, the combination of a series of weights, cords leading from said weights to the various alarm-stations, a lever resting on said weights, an alarm-bell, a cord leading downward from said lever, pulleys 80 around which said cord passes upward and horizontally, an alarm-pulley around which said cord passes, tappet-pins projecting from said pulley, and levers operated by said tappets to sound an alarm on the bell, substantially as described. 85

5. In an alarm mechanism, the combination of a series of weights, a cord leading from each weight to a station from which an alarm may be sounded, a slotted, horizontal lever resting on said weights through which said cords 90 pass, a vertical arm on said lever having trunnions projecting into vertical slots in upright standards, parallel levers pivoted to said vertical arm, and parallel levers pivoted to the standards at one end and to the first-named 95 levers at the other, and a link connecting the outer ends of the two series of levers, substantially as described. 100

6. In an alarm mechanism, the combination with the front and back of a box having oppositely-located vertical grooves in their inner faces, weights arranged to travel in said grooves, a series of numbers on the outside of the front of the box indicating alarm-stations, a series of strip-covers pivoted to the outside of the front in position to cover said numbers when raised, and arms projecting at right angles to said covers through a slot in the front into the path of the weights, substantially as described. 105
